(57) **CLAIM**

We claim the ornamental design for a pollinating tool, as shown and described.

DESCRIPTION

FIG. 1 is an elevational view showing the pollinating tool at a 45 degree angle between the top and right side;

FIG. 2 is a left-side elevational view of FIG. 1;

FIG. 3 is a right-side elevational view of FIG. 1;

FIG. 4 is a rear elevational view of FIG. 1;

FIG. 5 is a front elevational view of FIG. 1;

FIG. 6 is an exploded top plan view of FIG. 1;

FIG. 7 is a bottom plan view of FIG. 1; and,

FIG. 8 is a perspective view thereof, illustrating the tool in a bent configuration.
